CLAIM

The ornamental design for a steam trap as shown and described.

DESCRIPTION

FIG. 1 is an isometric depiction of a first embodiment of a steam trap according to our new design;

FIG. 2 is an elevational view taken from the front of the steam trap as depicted in FIG. 1;

FIG. 3 is an elevational view taken from the rear of the steam trap as depicted in FIG. 1;

FIG. 4 is an elevational view taken from the right side of the steam trap as depicted in FIG. 1;

FIG. 5 is an elevational view taken from the left side of the steam trap as depicted in FIG. 1;

FIG. 6 is an elevational view taken from the top of the steam trap as depicted in FIG. 1;

FIG. 7 is an elevational view taken from the bottom of the steam trap as depicted in FIG. 1;

FIG. 8 is an isometric depiction of a second embodiment of a steam trap according to our new design;

FIG. 9 is an elevational view taken from the front of the steam trap as depicted in FIG. 8;

FIG. 10 is an elevational view taken from the rear of the steam trap as depicted in FIG. 8;

FIG. 11 is an elevational view taken from the right side of the steam trap as depicted in FIG. 8;

FIG. 12 is an elevational view taken from the left side of the steam trap as depicted in FIG. 8;

FIG. 13 is an elevational view taken from the top of the steam trap as depicted in FIG. 8; and,

FIG. 14 is an elevational view taken from the bottom of the steam trap as depicted in FIG. 8.

The broken lines in the drawings illustrate portions of the steam trap that form no part of the claimed design.

1 Claim, 14 Drawing Sheets
